2 SHEETS—SHEET 2.

UNITED STATES PATENT OFFICE.

WARD S. IRELAND, OF ST. LOUIS, MISSOURI, ASSIGNOR TO NATIONAL SHORTHAND MACHINE COMPANY, OF ST. LOUIS, MISSOURI, A CORPORATION OF DELAWARE.

TYPE-WRITING MACHINE.

1,278,473.

Specification of Letters Patent. Patented Sept. 10, 1918.

Application filed November 18, 1916. Serial No. 132,084.

To all whom it may concern:

Be it known that I, WARD S. IRELAND, a citizen of the United States of America, a resident of the city of St. Louis, State of Missouri, have invented certain new and useful Improvements in Type-Writing Machines, of which the following is a full, clear, and exact description, reference being had to the accompanying drawings, forming a part of this specification.

My invention relates to improvements in typewriting machines, and more particularly to paper feeding mechanism adapted for use in shorthand machines. One of the objects of the invention is to produce a strong, simple and accurate paper feeding device adapted to coöperate with the finger keys of a shorthand machine, and adapted to advance the paper a fixed distance during each key operation. The paper feeding device moves a fixed distance during each operation, and since the paper is positively prevented from slipping by the positive gripping devices, it travels a fixed distance during each operation. An accurate paper feeding device of this kind is particularly adapted for use in a shorthand machine wherein the paper is to be fed step by step (line by line) in response to the key operations.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a longitudinal section of a shorthand machine embodying the features of my invention.

Fig. II is a vertical section taken approximately on line II—II, Fig. I.

Fig. III is a detail view showing the paper feeding device in its normal or starting position.

Fig. IV is a view showing the parts as they appear at the end of the paper feeding operation.

Fig. V shows the parts in the positions they occupy during their backward, or reverse turn movement.

Fig. VI is a fragmentary view of the means for preventing retrograde movement of the paper.

Fig. VII is a fragmentary view illustrating the roll of paper and the friction devices associated therewith.

To illustrate the invention, I have shown a shorthand machine provided with a housing 1, a type holder 2 arranged in said housing (Fig. I), a type bar 3 loosely secured in said type holder, a yieldable abutment 3' arranged in the type holder and fitted to the type bar 3, and an inking ribbon 4 adjacent to the line of type on the type bar 3. The paper passes from a supply roll A, over a roller 5, under and partially around a roller 5', in front of and over an uncurling device 6 and then to the paper feeding device whereby it is unwound from the roll and fed through an opening 7 at the rear of the machine.

The key actuated devices preferably include a series of angular levers each having an upwardly extending arm 8 at its front end (Fig. I) and a character key 9 at the upper end of said arm. Any suitable shorthand code may be used, and if desired, the keys may be provided with characters corresponding to the line of type characters on the type bar 3. Each key lever includes an arm 10 extending rearwardly from its arm 8 and an arm 11 extending upwardly from the rear portion of said arm 10. The series of key levers is pivotally supported by a pivot member 12 located at the junctions of the lever arms 10 and 11. The upper end of each lever arm 11 is provided with a forwardly extending hammer 13 which lies adjacent to the type 3. Restoring springs 14 (Fig. I) connected to the lever arms 10, tend to retain the upper ends of lever arms 11 in engagement with an abutment 15.

When one of the finger keys 9 is depressed, the key lever associated therewith turns about the axis of pivot member 12 and a printing hammer moves toward the type 3, thereby forcing the paper and inking ribbon toward the type and printing one of the type characters on the paper. The key levers may be operated independently of each other, or any desired number of key levers may be operated simultaneously.

The universal bar associated with the key levers includes a transverse abutment 18 ar-

ranged in front of the series of lever arms 11 and engaging all of said lever arms. The universal bar also includes a pair of arms 20 and 21 pivotally supported by the pivot member 12 arranged on opposite sides of the lever arms 11, and secured near their upper ends to the transverse abutment 18. 23 designates a restoring spring (Fig. I) connected to the universal bar and tending to 10 retain it in the position shown in the drawings. The transverse abutment 18, forming part of the universal bar structure is so arranged that the universal bar will move in response to movements of any one of the 15 key levers.

24 designates a key lever guide, arranged near the junctions of the lever arms 10 and 11, and adapted to receive the wings which extend rearwardly from the key levers and 20 universal bar, as shown in Fig. I.

The paper feeding device preferably comprises a stationary supporting frame having a pair of side members 25, secured at their lower ends to the key lever guide 24. 25 A main pivot rod 26, extending across the stationary frame, is mounted in bearings at the upper ends of the side members 25. A pair of carrier arms 27, pivotally supported by the main pivot rod 26, extend upwardly 30 from said pivot rod and constitute a support for the gripping elements. Each carrier arm 27 is preferably provided with an upper gripping link 28, a lower gripping link 29, and operating links 30 and 31 connecting said gripping links to an operating lever 32. Pivots 33 and 34 connect the gripping links to the carrier arms 27, the operating links 30 and 31 being connected to the upper ends of levers 32 by means of a 35 pivot 35. It will be noted that the gripping links 28 and 29 are connected to the operating links 30 and 31, so as to form a pair of toggles, and that the toggle structure may be operated to force the gripping 40 links 28 and 29 toward and away from each other. The margins of the strip of paper A' pass between the pairs of gripping links 28 and 29 as shown most clearly in Figs. II and III. Pivot members 37 connect the 45 toggle operating levers 32 to the carrier arms 27.

The driving device for transmitting energy from the universal bar to the toggle operating levers 32, comprises a sleeve 38 mounted on the main pivot rod 26, and having a pair of upwardly extending arms 39 to which the lower ends of the toggle operating levers 32 are pivoted, the upper end of each arm 39 being provided with a pin 55 40 which lies in a slot at the lower end of a lever 32. An arm 41, extending downwardly from the sleeve 38, is connected to the universal bar by means of a yieldable link 42. 43 designates restoring springs, 60 connected to the carrier arms 27 and tend-

ing to retain the paper feeding elements in the positions shown in Figs. I and III.

To clearly understand the operation of the paper feeding device, it should be borne in mind that the gripping links 28 and 29, as 70 well as the operating levers 32, are pivotally supported by the carrier arms 27, the latter being supported by the main pivot 26. When the parts occupy their normal, or starting position, (Fig. III) the restoring 75 springs 43 tend to pull the carrier arms 27 forwardly. At this time the arms 39, extending upwardly from sleeve 38, are stationary and the restoring springs 43 tend to pull all of the gripping elements forwardly 80 independently of said arms 39. Since the pivot members 37, connecting the levers 32 to the carrier arms 27, are pulled forwardly while the levers are engaged with the stationary pins 40, the springs 43 tend to turn 85 said levers 32 about their axes, the result being that the upper ends of levers 32 are forced forwardly so as to force the gripping links into engagement with the paper when the parts occupy their starting position 90 (Fig. III).

In feeding the paper, the universal bar pulls the link 42 in the direction indicated by the arrow in Fig. III, thereby forcing the gripping elements into engagement with 95 the paper, and at the same time feeding the paper. The gripping action is due to the fact that the pivot pins 40, carried by arms 39, tend to turn the toggle operating levers 32 about the axes of their pivots 37, thereby 100 forcing the gripping links toward each other and into engagement with the paper. The energy for driving the carrier arms 27, during the operation of feeding the paper, is transmitted from the universal bar, through 105 link 42, arm 41, sleeve 38, arms 39, pivot pins 40, and then to the toggle operating levers 32. The toggle operating levers, therefore, serve as means for transmitting energy to the gripping links to force them 110 into engagement with the paper, at the same time transmitting energy to the carrier arms 27, so as to advance the paper while it is firmly gripped between the links. It may be noted that the gripping links are forced 115 backwardly with respect to the movement of the paper, however, these links actually travel with the carrier arms 27 to pull the paper in the desired direction. Fig. IV illustrates the parts as they appear at the 120 end of each feeding operation. When the universal bar returns to its normal position, it pushes the link 22 in the direction indicated by the arrow in Fig. V, thereby turning the arms 41 and 39 about the axis of 125 pivot 26. At the beginning of this return movement the pivot pins 40 at the upper ends of arms 39, are thrown very quickly from the position shown in Fig. IV to the position shown in Fig. V, thus turning the 130

toggle operating levers 32 on their pivots 37 to release the gripping links 28 and 29 from the paper. The means for restoring the universal bar is preferably designed to 5 act quicker than the springs 43 which restore the carrier arms 27, the object being to retain the gripping links in their inoperative positions (Fig. V) while the springs 43 are pulling the carrier arms 27 to their starting 10 positions. It is to be understood, however, that the gripping links are inclined in such a manner that they will not pull the paper very severely in returning to their starting position, even though the means for restoring 15 the universal bar does not act more rapidly than the light springs 43 which restore the carrier arms 27.

The means for preventing retrograde movement of the paper comprises a pawl 20 50, pivoted to a stationary arm 51, and engaging the paper, as shown most clearly in Fig. VI.

The inner end of the strip of paper is firmly secured to a core 55 (Figs. I and 25 VII) provided at its ends with friction members 56 and 57 which turn with the roll of paper. A friction member 58, engaging the friction member 56, is rigidly secured to a stationary arm 59. 60 designates a yieldable friction member slidably fitted to a spring pocket at the lower end of a stationary arm 61. A spring 62 forces the friction member 60 into engagement with the friction member 57, at 35 the same time forcing the friction member 56 into engagement with the stationary friction member 58. The roll of paper is supported by pins, or trunnions 63 which extend from the friction members 58 and 40 60. The spring pressed friction elements tend to prevent the roll of paper from turning, and upon the operation of the paper feeding device the paper is pulled along the uncurling device 6 (Fig. I), said uncurling 45 device being a small rod located above the printing elements and fixed to stationary parts of the machine. In passing over the uncurling device 6, the strip of paper is turned abruptly in a direction opposed to 50 the direction in which it was wound on the roll. By holding the paper under tension and pulling it over the uncurling device in the manner illustrated, the paper is uncurled and fed from the machine in an 55 absolutely uncurled condition. My paper feeding device is well adapted to pull the paper against the resistance offered by the friction elements, for the paper is firmly gripped between the inclined links 28 and 60 29 and the resistance offered to the movement of the paper tends to pull the links backwardly with respect to the movement of the paper, thus tending to grip the paper more firmly between the gripping 65 faces of said links.

The paper straightening device herein disclosed is claimed in an application for patent filed by me on May 19, 1917, Serial No. 169,620. The printing elements are claimed in an application filed by me on 70 November 18, 1916, Serial No. 132,076.

I claim:—

1. In a typewriting machine, a paper feeding device comprising a carrier, gripping elements pivoted to said carrier, and 75 operating means for forcing said gripping elements toward each other to grip the paper, thereby actuating the carrier to feed the paper, said carrier being movable in response to the movement of said operating 80 means after the gripping elements have been forced into engagement with the paper.

2. In a typewriting machine, a paper feeding device comprising a carrier, gripping elements pivoted to said carrier, and 85 operating means connected to said gripping elements and adapted to force them toward each other to grip the paper, said parts being so arranged that the carrier 90 will move in response to the movement of said operating means after the gripping elements have been forced into engagement with the paper.

3. In a typewriting machine, a paper 95 feeding device comprising a carrier, gripping links pivoted to said carrier, operating links pivoted to said gripping links, and means for actuating said operating links to force the gripping links into 100 engagement with the paper, said carrier being movable in response to the movement of said means after the gripping links have been engaged with the paper.

4. In a typewriting machine, a paper 105 feeding device comprising a carrier, gripping links pivoted to said carrier, operating links pivoted to said gripping links, an operating lever secured to said operating links, and means for actuating said operating 110 lever to move all of said parts to feed the paper, thereby forcing said gripping links into engagement with the paper.

5. In a typewriting machine, a paper feeding device comprising a carrier, gripping 115 links pivoted to said carrier, operating links pivoted to said gripping links, an operating lever secured to said operating links, a pivot member securing said operating lever to said carrier, and means for actuating 120 said operating lever to move all of said parts to feed the paper, thereby forcing said gripping links into engagement with the paper.

6. In a typewriting machine, a paper 125 feeding device comprising a carrier, a main pivot supporting said carrier, gripping links pivoted to said carrier, operating links pivoted to said gripping links, an operating lever pivoted to said operating 130

- links and also pivoted to said carrier, and means for actuating said operating lever to force said gripping links into engagement with the paper, at the same time 5 moving said carrier, gripping links and operating lever about the axis of said main pivot.
7. In a typewriting machine, a paper feeding device comprising a carrier, a main pivot supporting said carrier, gripping links pivoted to said carrier, operating links pivoted to said gripping links, an operating lever pivoted to said operating links and also pivoted to said carrier, and means 10 for actuating said operating lever to force said gripping links into engagement with the paper, at the same time moving said carrier, gripping links and operating lever about the axis of said main pivot, and a 15 spring for restoring said carrier.
8. In a typewriting machine, a paper feeding device comprising a carrier including a pair of side members, a pivotal support for said carrier, gripping links pivoted to said 20 side members and adapted to grip the side margins of the paper, operating levers pivoted to said side members and secured to said gripping links, means for actuating said operating levers to force the gripping links into engagement with the paper, thereby moving said carrier to feed the paper, 25 and a spring for restoring said carrier.
9. In a typewriting machine, a paper feeding device comprising a carrier, gripping elements including a toggle link carried by said carrier and adapted to grip the paper, and means for forcing said toggle link into engagement with the paper, at the same time actuating said carrier to feed the 30 paper.
10. In a typewriting machine, a paper feeding device comprising a carrier, gripping elements including a pair of toggle links pivotally supported by said carrier 35 and adapted to grip the paper, and means for forcing said toggle links toward each other and into engagement with the paper, at the same time actuating said carrier to feed the paper.
11. In a typewriting machine, a paper feeding device comprising a carrier, a paper gripping device including toggle members carried by said carrier, and means for actuating said toggle members to secure the 40 paper to said carrier, at the same time shifting said carrier and toggle members to feed the paper.
12. In a typewriting machine, a paper feeding device comprising a carrier, a pivotal support for said carrier, a paper-gripping device including toggle members pivoted to said carrier, a toggle operating member pivoted to said carrier, and means 45 for actuating said toggle operating member to grip and at the same time feed the paper.
13. In a typewriting machine, a paper feeding device comprising a carrier, a main pivot supporting said carrier, a paper gripping device including toggle links pivoted to said carrier, a toggle operating lever for 50 actuating said toggle links to force the paper gripping device into engagement with the paper, and means for actuating said toggle operating lever so as to move said carrier and toggle links about the axis of said 55 main pivot.
14. In a typewriting machine, a paper feeding device comprising a carrier having a pair of side members, two pairs of toggles supported by said carrier, each pair of toggles 50 being pivoted to one of said side members, a toggle operating device, and means for transmitting energy to said toggle operating device so as to feed the paper, at the same time forcing said toggles into engagement with the paper.
15. In a typewriting machine, a paper feeding device comprising a carrier, a main pivot member supporting said carrier, a toggle operating lever pivoted to said carrier, 60 a pair of toggles connecting said toggle operating lever to said carrier, and means for actuating said toggle operating lever to force the toggles toward each other and into engagement with the paper thereby moving 65 all of said parts about the axis of said main pivot.
16. In a typewriting machine, a paper feeding device comprising a carrier, a main pivot supporting said carrier, a lever pivoted to said carrier, toggle links pivoted to said carrier and adapted to cooperate with each other to grip the paper, links connecting said toggle links to said lever, and an operating device fitted to said lever and 70 adapted to actuate the same to force said toggle links toward each other, all of said parts being movable about the axis of said main pivot in response to the movement of said operating device after the toggle links 75 have been forced into engagement with the paper.
17. In a typewriting machine, a paper feeding device comprising a carrier, gripping links pivoted to said carrier so as to 80 grip the paper during the paper feeding operations, said gripping links being inclined so that the resistance offered by the paper tends to force them into engagement with the paper, and means for operating said carrier.
18. In a typewriting machine, a paper feeding device comprising a carrier, gripping elements including a pair of toggle links pivotally supported by said carrier 85 and adapted to grip the paper, said toggle links being inclined so that the resistance offered by the paper tends to force their gripping faces into engagement with the paper, and means for actuating said carrier 90

and toggle links to grip and at the same time feed the paper.

19. In a typewriting machine, a paper feeding device comprising a pair of links 5 adapted to grip the paper during the paper feeding operations, and means for forcing the said links backwardly with respect to the movement of the paper so as to grip and feed the paper.

10 20. In a typewriting machine, a paper feeding device comprising a carrier, a pair of gripping links pivotally supported by said carrier, and means for forcing the gripping faces of said links backwardly 15 with respect to the movement of the paper, so as to grip the paper and actuate the carrier to feed the gripped paper.

21. In a typewriting machine, a paper feeding device comprising an oscillatory 20 carrier, a pair of gripping links pivoted to said oscillatory carrier, and means for forcing the gripping faces of said links back-

wardly with respect to the movement of the paper, thereby forcing said links toward each other to grip the paper, and transmitting power through the links to move all of said parts about the axis of said carrier to feed the paper. 25

22. In a typewriting machine, a paper feeding device comprising a carrier, a 30 pivotal support for said carrier, a paper gripping device including toggle members pivoted to said carrier, a toggle operating member carried by said carrier, and means for actuating said toggle operating member 35 to force said toggle members backwardly with respect to the movement of the paper, thereby forcing said toggle members toward each other to grip the paper between them and then transmitting power through the 40 links to operate said carrier to feed the paper.

WARD S. IRELAND.
